(57) **CLAIM**

We claim the ornamental design for a meat tenderizer with spiked roller and marinade-dipping handle, as shown and described.

DESCRIPTION

FIG. 1 is a perspective view of a meat tenderizer with spiked roller and marinade-dipping handle showing our new design in use; the broken lines depict environmental structure for illustrative purposes only and form no part of the claimed design;

FIG. 2 is a front elevational view thereof, the rear elevational view being identical thereto;

FIG. 3 is a side elevational view thereof, the elevational view of the opposite side being identical thereto;

FIG. 4 is a top plan view thereof; and,

FIG. 5 is the bottom plan view thereof.
